UNITED STATES PATENT OFFICE.

ALFRED A. BROOKS, OF WELLSVILLE, NEW YORK, ASSIGNOR TO GENERAL ELECTRIC COMPANY, A CORPORATION OF NEW YORK.

CENTRIFUGAL COMPRESSOR.

Application filed May 16, 1922. Serial No. 561,397.

To all whom it may concern:

Be it known that I, ALFRED A. BROOKS, a citizen of the United States, residing in Wellsville, in the county of Allegany, State 5 of New York, have invented certain new and useful Improvements in Centrifugal Com-
pressors, of which the following is a specifi-
cation.

The present invention relates to centrifu-
10 gal compressors, such as air or gas compres-
sors and particularly centrifugal compres-
sors having axial inlet impellers and sta-
tionary inlet guide vanes for directing the
fluid being pumped into the eye of the im-
15 peller. In such compressors the impeller
vanes are arranged around the hub of the
impeller and extend in a generally radial di-
rection. They receive the fluid being
20 pumped at their radially inner ends and dis-
charge it at their radially outer ends, i. e.,
at the periphery of the impeller.

The object of my invention is to provide
an improved structure or arrangement of
25 stationary inlet guide vanes for compressors
of this type and for a consideration of what
I believe to be novel and my invention at-
tention is directed to the following descrip-
tion and the claims appended thereto.

In the drawing, Fig. 1 is a face view of
30 the inlet side of an inlet or guide vane struc-
ture embodying my invention; Fig. 2 is a
similar view of the discharge or exit side;
Fig. 3 is a sectional view of a compressor
35 provided with stationary guide vanes em-
bodying my invention; Fig. 4 is a perspec-
tive view of a guide vane, and Figs. 5, 6
and 7 are enlarged diagrammatic sectional
views taken on lines 5—5, 6—6 and 7—7, re-
spectively, of Fig. 3.

40 Referring to the drawing, 10 indicates the
casing of a compressor having the usual dis-
charge scroll 11 which receives the air from
the periphery of the impeller and conveys it
to the discharge opening. Suitably mount-
45 ed in casing 10 is a shaft 12 upon which is
mounted an impeller comprising a hub 13
and radially extending vanes 14. An im-
peller which receives fluid to be pumped on
both sides is illustrated, the entrance edges of
50 the vanes being indicated at 15. At the en-
trance edges of the impeller are stationary
inlet guide vanes 16 carried by spaced con-
centric rings 17. The entrance edges of the

inlet guide vanes are indicated at 18 and
the exit edges at 19.

With an impeller of this type the velocity
of the radially outer portions of its entrance
edges 15 is greater than that of the radially
inner portions, there being a gradually in-
creasing velocity from the inner edge ra-
dially outward due to the increasing diam-
eter. Also with stationary inlet guide vanes
the absolute velocity developed by the fluid
being pumped is the same at all points at
the exit edges of the inlet guide vanes be-
cause all points in that plane are in free
communication with each other and are sub-
ject to the same drop in pressure produced
by the impeller.

According to my invention I so shape the
stationary inlet guide vanes that the result-
ant relative velocities between the absolute
velocity of the fluid leaving the exit edges
of the guide vanes and the velocities of the
50 entrance edge of the eye of the impeller is
at all points axial. This is illustrated in
Figs. 5, 6 and 7 where in the diagrams W
is the velocity of the entrance edge of the
impeller at the particular point on which
the section is taken, V is the absolute veloc-
ity of the fluid being pumped at the exit
edges of the inlet guide vanes, and R is the
resultant air velocity relative to the impeller
entrance edge. To obtain this result the
stationary guide vanes take the form of
warped surfaces somewhat resembling heli-
coidal surfaces. One of these vanes is
70 shown in perspective in Fig. 4. From the
sections shown in Figs. 5, 6 and 7 it will be
seen that the discharge angle of the entrance
vanes is least at the hub and gradually in-
creases toward the outer end.

Viewed from a different aspect the sta-
tionary inlet guide vanes are so shaped or
warped as to give a graduation of the tan-
gential component of the exit velocity from
them which corresponds to the velocity of
the entrance edge of the impeller.

By this arrangement the fluid being
pumped is directed evenly and without shock
100 to the impeller and in a direction to give
the highest efficiency in operation.

In accordance with the provisions of the
patent statutes, I have described the prin-
ciple of operation of my invention, together
105 with the apparatus which I now consider to

represent the best embodiment thereof, but I desire to have it understood that the apparatus shown is only illustrative and that the invention may be carried out by other means.

What I claim as new and desire to secure by Letters Patent of the United States, is:—

1. The combination with a centrifugal compressor having an impeller which has an axially facing inlet at its central portion and a peripheral discharge, of stationary guide vanes for directing fluid to the inlet, said vanes being twisted to provide helicoidal surfaces such that the resultant relative velocities between the absolute velocity of the fluid at the exit edges of the vanes and the velocities at the entrance edges of the eye of the impeller are substantially axial.

2. A centrifugal compressor having stationary inlet guide vanes which are warped from their inlet to their exit edges to such an extent that the resultant relative velocities between the absolute velocity of the fluid at the exit edges of the vanes and the velocities at the entrance edges of the eye of the impeller are substantially axial.

3. A centrifugal compressor having stationary inlet guide vanes which are warped from their inlet to their exit edges to such an extent that the tangential component of the exit velocity at any point along the discharge edge of the vanes corresponds substantially to the velocity of the corresponding point at the entrance edge of the impeller.

In witness whereof, I have hereunto set my hand this 12th day of May, 1922.

ALFRED A. BROOKS.
